AIR HANDLING AND DUST COLLECTING
MECHANISMEdward L. Anderson, Detroit, Mich., assignor to
American Blower Corporation, Detroit, Mich.,
a corporation of Delaware

Application July 24, 1937, Serial No. 155,458

6 Claims. (Cl. 183—80)

This invention relates to air conditioning and, in particular, to air handling and dust collecting mechanism.

It is an object of this invention to provide a combined volume control and dust collector.

It is a further object of this invention to provide inlet damper control means for controlling the volume of air supplied to the fan means.

It is a further object of this invention to provide means for maintaining the efficiency of a fan above that achieved with ordinary design of dampers, irrespective of the change of volume of air supply by imparting to the fan inlet air a preliminary whirl before it enters the eye of the fan.

It is further object of this invention to provide dust collector means adapted to skim from the air in a fan inlet chamber, dirt, dust and other foreign material for the purpose of cleaning the air supplied to the fan, for the prevention of damage to the fan, and/or for the recovery from the air of materials suspended therein.

It is a further object of this invention to provide apparatus capable of functioning as a fan air inlet volume control and also as skimming means.

It is a further object of this invention to provide such means wherein an adjustable skimmer is provided, which will be automatically extended upon increase of volume of inlet air due to its cooperation with the air inlet control.

It is a further object of this invention to provide a single means performing the function of fan inlet volume control means and also skimming means.

These and other objects and advantages will appear from the following description taken in connection with the drawings.

In the drawings:

40 Figure 1 is an elevational view of fan structure having the apparatus of this invention incorporated therein;

Figure 2 is a section taken on the line 2—2 of Figure 1;

45 Figure 3 is an enlarged fragmentary sectional view taken on the line 3—3 of Figure 1;

Figure 4 is an enlarged elevational view, in section, of structure shown in Figure 1; and

50 Figure 5 is a section through a modified form employing guide vanes at the inlet to the fan.

Referring to the drawings in detail and with reference particularly to Figure 1, the fan is provided with a casing or housing 1 of volute shape having an air outlet 2. Rigidly secured at each side of the fan housing 1 in any suitable manner,

as by bolts or welding, is an air inlet box or chamber 3. Each air inlet box 3 is provided with an air inlet opening 4 and to the outside wall of each inlet box 3 is rigidly secured a bearing member 5. The bearing members 5 support the fan shaft 6 which has the fan rotor or wheel 7 rigidly secured in suitable manner to the central portion thereof and disposed within the fan housing 1.

Each bearing 5 rotatably supports the hub 9 of a gear 8, which is spaced therefrom by means of bearing members 10. Rigidly secured to each gear 8 is a substantially semi-circular back plate 11 having rigidly secured thereto an inlet control plate 12 of substantially semi-circular section, as shown in Figure 2. The edges of the back plate 11 extend outwardly beyond the inlet control plate to form an annular flange 13 which cooperates with a flange 14 provided on the inner surfaces of each inlet box 3, as shown in Figure 1. The inlet control plates 12 are adapted to form two chambers in each inlet box 3, namely, the inlet chamber 3a which communicates with the air inlet 4, and the fan chamber 3b which communicates, through the inlet throat 24, with the fan rotor 7 in the fan casing 1, and to control communication therebetween. The back plates 11 and attached inlet control plates 12, which are rigidly secured to the gears 8, are rotatable therewith and remote control means for adjusting the inlet control plates is provided, each of which comprises a gear 15 meshing with a gear 8 and rigidly secured to a stub shaft 16 rotatably supported in the bearing 17 secured in the outer wall of each inlet box 3. At its outer end, each stub shaft 16 has a gear 18 rigidly secured thereto, 35 which meshes with a gear 19 secured to the shaft 20 of a reversible electric motor 21 which is rigidly secured to the supporting bracket 22. Each supporting bracket 22 is rigidly secured to the outer surface of a side wall of the air inlet box 3. 40

The reversible electric motors 21 are preferably provided with suitable control circuits, by means of which they may be manually or automatically controlled from a remote station to adjust the inlet control members comprising back plates 11 45 and attached control plates 12 by rotation of the gears 8, for the desired amount through the above described gear train. Each inlet box 3 is provided with a dust take-off duct 23 which is substantially tangentially arranged with respect to the adjustable air inlet control plate 12 of each inlet box 3. The inlet throats of the fan are designated 24. The direction of rotation of the fan is indicated by an arrow in Figure 2, from the structure of which the inlet throat 24 has been 55

omitted for the sake of clearness. The inlet control members comprising inlet control plates 12 and supporting back plates 11 are adjustable in opposite directions, as indicated by the arrows 5 in Figure 2, throughout 360 degrees of arc. It will be apparent that the arcuate plate 12 may be rotated a considerable distance, right or left, from the position shown by the full lines in Figure 2 and still perform its dual function of controlling 10 the amount of air passing into the fan chamber and skimming the outer layer of dust. As long as the forward edge of the plate, as considered from the direction of the moving air, is adjacent to the curved or arcuate portion of the casing 3, 15 the plate will serve to skim the dust from the incoming dust-laden air. It is further evident that the air in passing through the inlet 4, first, strikes the curved surface of the plate 12 and thus is given a partially rotary movement. The air then enters the space between the edge 12a and the casing, and follows the curvature of the 20 arcuate portion of the casing to increase the preliminary whirling effect.

The path of air from the air inlet openings 4 to the air outlet openings 2 is indicated by arrows 25 in Figures 1 and 2. The distance between the lower edge 12a of the inlet control plate 12 and the adjacent wall of each air inlet box 3 determines the volume of air supplied from the inlet 30 chamber 3a through this passage and through the corresponding inlet throat 24 to the fan. The upper edge 12b of each inlet control plate 12 cooperates with the walls of the air inlet 35 boxes 3 to form an extension of the dust take-off duct 23 and to skim from the inlet air particles of dust, dirt and/or foreign material which is centrifugally separated from the air supply to the fan by reason of the preliminary whirl imparted to the air passing from the air inlet chamber 3a through the passageway between the edge 12a of the plate 12 and the cooperating inlet box wall to the fan chamber 3b and thence to the inlet throat 24. It is obvious that, if there is no 40 portion of the plate in the lower part of the casing, the plate does not perform the additional function of controlling the volume of air passing through the inlet box. However, under the circumstances, the plate may still serve to skim the dust from the incoming stream of dust and air if the forward edge of the plate is positioned to the right of the dust take-off, in which case the outer surface of the plate will serve in conjunction with the casing to guide the skimmed 45 dust to the take-off duct.

It will thus be seen that the inlet control plates 12, in addition to controlling the volume of inlet air, impart to the inlet air a preliminary whirl which centrifugally separates suspended dirt 50 and/or foreign material therefrom and also functions as a skimmer and cooperates with the walls of the inlet box 3 to convey this skimmed or separated material to the dust take-off duct 23. The dust take-off duct 23 is, of course, connected to any suitable collecting means.

Attention is particularly directed to the fact 55 that, when the inlet control plate 12, as seen in Figure 2, is rotatably adjusted in clockwise direction, the distance between the lower edge or lip 12a thereof and the wall of the inlet box is increased whereby to increase the passageway between the inlet chamber and the fan chamber and thus increase the volume of air supplied to the fan. At the same time, the upper edge or 60 lip 12b of the plate 12 is extended toward the pas-

sageway between the inlet chamber and the fan chamber. By means of the remote control means provided, the adjustment of the inlet control plates may be made from any desirable point or station and, due to the provision of the gear train 5 between each control or adjusting motor 21 (which is preferably reversible) and its back plate rotating gear 8, extremely accurate adjustments of the plates may be made.

While the principles of this invention have been 10 shown as applied to a double inlet fan, it is, of course, to be understood that they are applicable to a single inlet fan, in which case, only a single inlet box need be provided.

By referring to Figure 5 it will be observed that 15 this modification shows the use of inlet vanes 25 which are located in the inlet passageway 24. Thus the preliminary whirl given to the air by the positioning of the damper in the inlet passageway 3a, as at 12a, is continued and increased by the inlet vanes 25.

It will, of course, be understood that the above-described structure is merely illustrative of the manner in which the principles of my invention may be carried out and that I desire to comprehend within my invention such modifications as come within the scope of the claims and the invention.

Having thus fully described my invention, what I claim as new and desire to secure by Letters 30 Patent is:

1. In combination, a fan casing with a rotor therein, an air inlet box adjacent said fan casing for supplying air to said rotor, a dust take-off duct extending from said inlet box, and an adjustably mounted curved plate in said inlet box adapted to provide a substantially cylindrical space concentric with the fan casing between the inlet box and the outlet edge of the plate forming a tangential extension for said dust take-off duct, 40 the lower end of said plate cooperating with the nearest side of the inlet box to cause dust-laden air to enter the cylindrical space out of direct line with said space, the upper end of said plate being adapted to skim dust from the air and to convey 45 it through said tangential extension to the dust take-off duct.

2. A combined fan and dust separator unit comprising a fan chamber and air inlet chambers mounted on each side of the fan chamber, all of 50 said chambers communicating with one another and having a cylindrical configuration with an axis in common, a fan in said fan chamber mounted on a shaft which extends along the common axis into the inlet chambers, and means 55 including arcuate members carried by said shaft and positioned in each of said inlet chambers for skimming the dust from the dust-laden air entering the inlet chambers, each of said arcuate members being rotatable on said shaft to a position such that one end of the member cooperates with the inlet chamber to direct the incoming air initially to a direction away from the eye of the fan, and the opposite end of the member serves to skim the dust from the dust-laden air as it 60 enters the eye of the fan.

3. A combined fan and dust separator unit comprising a fan housing containing a fan provided with an eye, an air inlet chamber of curved configuration communicating with said eye, and 70 means including a curved plate concentrically mounted within said chamber for limiting the air inlet of the chamber to a position out of direct line with respect to the eye of the fan, whereby one edge of the plate cooperates with one side of 75

- the chamber to cause the dust-laden air to enter the chamber in a tangential direction and the opposite edge of the plate is caused to skim dust from the air entering the eye of the fan.
5. A combined fan and dust separator unit comprising a fan housing containing a fan provided with an eye, an air inlet chamber of curved configuration communicating with said eye, a dust take-off passage extending from said inlet 10 chamber, and a curved plate in said chamber supported for adjustment swingably about the eye of the fan, the lower end of said plate cooperating with the nearest side of the inlet chamber to cause dust-laden air to enter the chamber 15 out of direct line with the fan eye, and the upper end of the plate being adapted to skim dust from the air and convey it to said dust take-off passage.
5. A combined fan and dust separator unit 20 comprising a fan chamber containing a fan provided with an inlet eye, an air inlet chamber having a curved wall portion opposite the inlet communicating with said eye and symmetrically dis-
- posed with respect thereto, and means including a curved plate mounted concentrically with respect to said eye and spaced from the wall for limiting the air inlet to a position such as to cause the stream of incoming dust-laden air to enter the chamber at an off-set position with respect to the eye of the fan, whereby dust is skimmed from the air by said plate.
6. A combined fan and dust separator unit comprising a fan housing containing a fan provided with an inlet eye, an air inlet chamber communicating with said eye and directly in line therewith, and means for directing the dust-laden gas entering said chamber away from said eye, said means comprising a plate with free opposite ends, one of said ends cooperating with the nearest side of the inlet chamber to direct the dust-laden gas away from said eye and the other end cooperating with other portions of said chamber to skim the dust from said gas before it enters the eye of the fan.

EDWARD L. ANDERSON.
